GARMENT RACK

Lewis W. Cohn, Chicago, Ill.

Application May 23, 1952, Serial No. 19,861

Term of patent 7 years

(Cl. D80—10)

To all whom it may concern:

Be it known that I, Lewis W. Cohn, a citizen of the United States, residing at Chicago, in the county of Cook and State of Illinois, have invented a new, original, and ornamental Design for a Garment Rack, of which the following is a specification, reference being had to the accompanying drawing, forming a part thereof.

Fig. 1 is a perspective view of a garment rack showing my new design;

Fig. 2 is a side elevation thereof;

Fig. 3 is a front elevation of said garment rack; and

Fig. 4 is a bottom plan view thereof.

I claim:

The ornamental design for a garment rack, as shown.

LEWIS W. COHN.
